(57) **CLAIM**

We claim, the ornamental design for a vacuum package machine, as shown and described.

DESCRIPTION

FIG. 1 is the front perspective view of a vacuum package machine showing our new design;

FIG. 2 is the front elevation view thereof;

FIG. 3 is the rear elevation view thereof;

FIG. 4 is the left-side elevation view thereof;

FIG. 5 is the right-side elevation view thereof;

FIG. 6 is the top-side plan view thereof;

FIG. 7 is the bottom-side plan view thereof; and,

FIG. 8 is a front elevation view thereof, showing the vacuum package machine in a refrigerator environment.

The surface treatment of the vacuum package machine shown in the figures forms no part of the claimed design, a vacuum package machine according to the claimed design may have any surface treatment.

The broken lines illustrating portions of the vacuum package machine are for environmental purposes only and form no part of the claimed design.
